UNITED STATES PATENT OFFICE.

CHARLES E. AVERY, OF TRENTON, NEW JERSEY, ASSIGNOR TO MANHATTAN ELECTRICAL SUPPLY COMPANY, INC., OF JERSEY CITY, NEW JERSEY, A CORPORATION OF MASSACHUSETTS.

ELECTROMAGNET.

1,338,548.

Specification of Letters Patent. Patented Apr. 27, 1920.

Application filed March 27, 1917. Serial No. 157,738.

To all whom it may concern:

Be it known that I, CHARLES E. AVERY, a citizen of the United States of America, and residing in Trenton, in the county of 5 Mercer and State of New Jersey, have invented a certain new and useful Improvement in Electromagnets, of which the following is a specification.

My invention relates to electromagnets 10 and particularly to alternating current magnets, the object of my invention being to so construct a magnet of this type as to eliminate the chatter of the armature and associated parts which is commonly incident to the operation of the magnet due to 15 the vibrations caused by the alternating current, and to secure an increased range of movement for the armature whether operated by direct or alternating current.

20 In the following drawings,

Figure 1 is a plan, with cover removed, of an electromagnet for operating a fire gong and in which my invention is embodied in one form;

25 Fig. 2 is a section through the magnet coils showing the armature and supporting brackets;

Figs. 3, 4 and 5 are sections on the lines 3—3, 4—4, and 5—5, Fig. 1 respectively;

30 Fig. 6 is a diagrammatic elevation of a modified construction;

Fig. 7 is a broken elevation at right angles to Fig. 6; and

Fig. 8 is an elevation and Fig. 9 a broken 35 plan of one of the coil spools.

One of the difficulties incident to the use of alternating current to energize electromagnets is the rapid oscillation constantly imparted to the armature during the maintenance of the field. When the armature operates a switch, this oscillation results in a poor contact at the point of engagement between the switch members. When the armature operates a gong hammer, it causes 40 the hammer head to tremble against the gong and produces a muffled instead of a clear sound. Various ways have been heretofore devised which meet this difficulty with more or less success, but none in so 45 simple and efficient a manner, I believe, as that for which I now ask the grant of suitable patent protection.

Briefly stated my invention consists in

so arranging the armature with relation to the magnetic field that upon energization 55 of the magnet, the armature passes through the area of greatest magnetic attraction to a point at which said attraction is practically counter-balanced by the effort (gravity, counterweight or spring) of the armature to return to normal position.

In the construction here shown the magnet comprises a pair of coils 10 and 11 supported within the casing 12 by brackets 13 and 14 of non-magnetic material, such as 65 brass. These coils are here shown wound in multiple, the lead wires 15 and 16 being connected to terminal plates 17 and 18 mounted on a block 19 of insulating material carried by the side wall of the casing 70 12 and to which the wire mains entering through the conduit 20 are connected.

The armature 21 is rigid with the spindle 22 pivoted on the bracket 23, and the gong hammer 24 is fast on the spindle 22 75 so that it is swung into contact with the gong 25 when the armature is drawn down as a result of the energization of the magnet by the operating current. The poles of the magnet core project beyond the ends of 80 the coils but the pole 26 a less distance than the pole 27. The ends of both poles are beveled to the inclination of the armature in its normal rest position so that the air gaps between the poles and the armature 85 are substantially equal at both points. The armature is pierced so that when operated the pole 26 passes into the armature and the pole 27 passes internally through it, the holes being somewhat larger than the poles 90 which cannot come in contact with the armature. A spring 28 may be attached at one end to the armature at 29 and at its other end 30 to the casing to counter-balance to a large extent the weight of the gong lever 95 24 and thus render the action of the armature more delicate. Less current is thus required to actuate the gong lever.

Upon the energization of the coils a magnetic field is created which is approximately 100 illustrated in Fig. 2. As indicated in the drawing, the armature normally lies beyond the area X of greatest magnetic effort. The throw of the armature, however, under the influence of the magnetic field, carries it not 105 only into this area but through it to a point

of rest against the non-magnetic bracket 14, at which point the magnetic attraction is substantially counter-balanced by the tendency of the lever 24 to return to its position of rest by gravity. The armature consequently lies quietly in this position without the usual tremble resulting from the oscillation of the alternating current in the magnet coils. It is emphasized that the bracket 14 is of brass, or other non-magnetic material, and has no influence upon the armature 21, as would be the case were the bracket of iron or like material.

In fire alarm systems a weak supervising current is constantly maintained on the signal circuit to insure the maintenance of the latter in operative condition. The position of the armature 21 must therefore be such with relation to the magnetic field that it is not materially affected by the slight pull of the field under the influence of the supervising current. On the other hand, it must be sufficiently close to the maximum effort of the field to respond at once and with certainty when the operating current is impressed upon the circuit. Moreover, its tendency to return to position of rest must be sufficiently strong to overcome the weak magnetic field caused by the supervising current so that upon the break of the operating circuit the lever returns to position, its inertia being sufficient to carry it through the area of greatest magnetic pull. This is true, even though the field resulting from the supervising current may be so strong that were the armature to be halted at the point of maximum attraction therein at the end of its operating stroke, its tendency to return would be insufficient to overcome the magnetic effort.

The invention is not applicable solely to magnets employed for the operation of gongs, since the magnet may with equal value be utilized to operate a contact lever or other member. It is applicable to all A. C. magnets in which the elimination of the vibration of the actuated member at the end of its stroke is desired.

It will be noted that the armature and the magnet core are both laminated, the advantages of which construction are well-known. It will also be noted that as an incident to the accomplishment of the result stated, the branch 27 of the magnet core extends beyond the outer face of the armature when the latter is operated by the magnet. This has a determining effect in locating the magnetic field in the desired area. The non-magnetic brackets 13 and 14 are split or slotted to avoid the formation of eddy currents which if present would require greater power to energize the magnet, as is well understood by those skilled in the art.

One detail of value in the construction of the magnet is illustrated in Fig. 8 and re-

lates to the spool upon which the magnet coil is wound. The hollow body 31 of the latter consists of a strip of sheet metal bent to rectangular shape, in cross section, the walls of which are offset at one end to form an outwardly extending flange 32 against which the disk head 33 freely rests. The other disk head 34 is slipped freely upon the opposite end of body 31 and tongues 35 then struck outward therefrom which forms retaining means to prevent the escape of the head 34. Both heads are retained in their extreme positions against the flanges 32 and 35 by the coil when the latter is wound on the spool. The projecting portion 36 of the spool body is engaged by the bracket 14 on which one end of the magnet is supported. In order to prevent the edges of the laminations of the core from coming into contact with the walls of the spindle 31 insulating strips 37 may be interposed. One of these strips is preferably located on the same side of the spindle as the spaced edges *a* and *b* of the sheet, thus serving to maintain these edges spaced apart and prevent the formation of eddy currents in the spindle.

In Figs. 6 and 7 I have illustrated diagrammatically a modified construction in which the armature 38 is mounted on an axis 39 parallel to the plane of the branches 26* and 27* of the core instead of at right angles thereto as in Figs. 1 to 5. The magnetic field is the same in this arrangement as in the one above described, and the location of the armature with reference thereto may be similarly predetermined. The advantage of the construction in Figs. 1 to 5 is merely one of greater leverage for the armature within a given space.

Various modifications in details of construction will readily occur to those skilled in the art which do not depart from what I claim as my invention.

I claim:

1. An alternating current magnet comprising magnet coils, pole pieces therefor projecting beyond the ends of the coils a sufficient distance to establish an area of maximum magnetic attraction beyond the ends of the coils, a rigid armature spaced from said poles but pivoted at a point such that, on excitation of the magnet, the armature is free to pass through said area of maximum attraction, together with rigid stop means halting said armature in stable position at a point at which the magnetic attraction is substantially counterbalanced by the effort of the armature to return to normal position.

2. In a construction such as specified in claim 1, a lever associated with said armature and moved to operative position by the latter on the excitation of the magnet.

3. In a construction such as specified in claim 2, a spring arm carried by said lever

and temporarily flexed into action by the impingement of the armature against its stop.

4. In a construction such as specified in claim 1, a lever rigid with said armature and extending on the opposite side of the pivotal mounting of the armature, said lever

being moved into operative position by the movement of the armature on the excitation of the magnet.

In testimony whereof I have signed my name to this specification.

CHARLES E. AVERY.
